CROSSTIE AND RAIL FASTENING MEANS

Elza C. Barnes, Attica, Ind.

Application November 26, 1945, Serial No. 630,717

9 Claims. (Cl. 238—275)

1

This invention relates to a metallic railway cross tie, wherein there are many advantages, particularly as compared to the formerly employed wood tie which is becoming increasingly harder to get, both in respect to quality and quantity.

An important advantage of the invention resides in the fact that the invention may be employed in place of the wood tie within a reasonable price comparison. Spikes are not employed, and the track gauge may be adjusted within predetermined limits and held in fixed dimension without having to employ any complicated mechanism. The rail rides on a plate taking the load to distribute it on the tie proper. The structure embodying the invention may be installed without having to lift or loosen the rails in any respect.

Parts are interchangeable one with the other so that there has to be no matching of right or left hand parts. The manufacturing of the structure embodying the invention is likewise simple requiring no precise dimensioning, but employing tolerances well within customary railroad practice. The rails may expand and contract longitudinally without distorting or stretching the rail hold-down means. A safety holding means for preventing expanding of the rails in case of bolt failure or bolt loosening is provided. Furthermore, the rail holding means will permit, if preferred, a slide movement of the rail as the train passes over the tie.

These and many more objects and advantages of the invention will become apparent to those versed in the art in the following description of one particular embodiment of the invention as now best known to me, as illustrated in the accompanying drawings, in which

Fig. 1 is a view in end elevation of a structure embodying the invention;

Fig. 2, a view on an enlarged scale in horizontal section on the line 2—2 in Fig. 1;

Fig. 3, a view in perspective of a rail anchor plate;

Fig. 4, a view in perspective of a rail clamp;

Fig. 5, a view in vertical section on the line 5—5 in Fig. 1;

Fig. 6, a view in top plan on a reduced scale of a rail section mounted on a tie in accordance with the invention;

Fig. 7, a view in vertical section through a rail with a curve clamp applied thereto;

Fig. 8, a sectional view similar to Fig. 5 but modified to show a single plate; and

2

Fig. 9, a top plan view of the modified form shown in Fig. 8, with the rail omitted.

Like characters of reference indicate like parts throughout the several views in the drawings.

The invention consists essentially of a channel iron turned with its legs upward and a rail anchor plate carrying rail clamps secured one to the other and to the channel iron in a most effective and novel manner. A channel iron 10 is selected to have a web 11 of sufficient width to provide for ample load bearing on the type of soil over which the track is built. The length of the channel iron 10 will approach that of the standard length of a customarily employed wood tie although it is believed that the extension of the end of the channel iron outside of the rail may be shortened in respect to the wood tie. Both rails of the track will be mounted in exactly the same manner, and therefore the description is made herein in reference to one rail only in respect to its mounting upon the channel iron 10.

Anchor plates 12 and 13 are provided to have a length sufficient to extend across the upturned ends of the legs 14 and 15 of the channel 10, the width of each plate 12 and 13 in the present illustration being the same so that when laid side by side over the legs 14 and 15, the ends of these plates will overhang the channel iron 10 by their ends, and the combined width will be such that outer side portions of the plates will extend beyond the base 16 of the rail 17. These anchor plates 12 and 13 are identical in shape and dimension whereby one may be used interchangeably with the other, including their appendages.

Referring to Fig. 3, the anchor plate 13 has a downwardly extending leg 18 of that length whereby the lower end provides a foot 19 that will rest on the top side of the web 11 when the under side of the plate 13 rests across the legs 14 and 15. The upper portion of this leg 18 is made to be of a width which will fit between the upper portions of the legs 14 and 15, and preferably a long fillet 20 is provided between the upper outer side of the leg 18 and the under side of the plate 13 to afford additional strength and rigidity to the plate 13 in respect to downward bending thereof. For convenience and saving of metal, the lower portion of the leg 18 is preferably reduced in width in respect to the distance between the legs 14 and 15.

From one end, herein shown as the right end, Fig. 3, of the upper portion of the leg 18 extends a pin 21 of any suitable conformation, herein shown as cylindrical, and with a rounded outer

end. The length of the cylindrical portion is made to be equal substantially to the thickness of either leg 14 or 15, the thickness of these legs being the same. The leg 15 is provided with a hole therethrough to receive the pin 21 and permit it to extend therethrough the length of its cylindrical portion. Insertion of this pin 21 in the hole, designated by the numeral 22, is accomplished by placing the plate 13 across the legs 14 and 15 in a diagonal position in respect to the longitudinal lengths thereof to enter the rounded end of the pin 21 in the hole and then the plate is swung around to the position of 90 degrees between the vertical plane of the face of the leg 18 and the plane of the outer side of the leg 15. In other words, the entrance of the pin 21 into and through the hole 22 is accomplished without having to spread apart the upper ends of the legs 14 and 15. Then in the same manner, the other anchor plate 12 is positioned across the legs 14 and 15 to bring its inner edge against the inner edge of the anchor plate 13 to have the downturned leg 23 to come into facile contact with the leg 18 and to have the pin 24 from the leg 23 inserted through the hole 25 provided in the leg 14. In this respect, it is to be noted that the hole 25 is offset in relation to the hole 22 longitudinally of the channel 10 to permit the abutment of one leg 18 against the leg 23 in the corresponding abutment of the plates 12 and 13 thereabove. As above indicated, the leg 23 and the pin 24 are exact counterparts of the leg 18 and its pin 21 in respect to contour and dimensions so that the entire unit in either case may be interchanged one with the other. This means that but one such unit need be made and carried in stock, and no difficulty then arises out on the roadway when the parts are installed.

Both anchor plates 12 and 13 are provided respectively with notches 26 and 27 entering from their longitudinal edges. A pair of clamps 28 and 29, each an identical counterpart of the other, is employed to interengage the rail 17 with the outer plates 12 and 13. As indicated in Fig. 4, where the clamp 28 is illustrated in perspective, the clamp in each instance has a downturned leg 30 with a face substantially parallel with the face of the leg 18 or 23 as the case may be. From the upper portion of the leg 30 the clamp extends diagonally upwardly and outwardly by a portion 31 from which a neck 32 extends upwardly with a width permitting it to be inserted slidably within the notch 26 or 27 as the case may be. From the upper end of the neck 32 an arm 33 is turned inwardly over and above and spaced from the portion 31. The clamps 28 and 29 are brought up on respective sides of the anchor plates 12 and 13, and a bolt 34 is passed through a hole 35 in the leg 30 and the hole 36 in the legs 18 and 23 as a means for drawing the clamp legs one toward the other and toward the intervening leg 18 and 23, Fig. 5. The clamp in each instance whether it be 28 or 29, is so proportioned that washers 37 and 38 may be employed in number as may be required on the bolt 34 as spacers between the respective brackets and the intervening legs.

The arms 33 are spaced from the centers of the holes 35 in the clamps that distance whereby they will fit over the top sides of the base 16 of the rail 17 and the inner face of the neck 32 will abut the vertical edges of that base 16. Then to secure the desired track gauge, the rail 17 will be shifted through its base 16 over the anchor plates 12 and 13 to the required dimension and

washers applied between the legs 30 of the clamps and the nut 39 drawn up on the bolt 34 to fix the rail at the location required. In other words by removing or adding washers 37 or 39 on either side of the legs 18 and 23, the clamps will be pushed to either side of the legs as may be desired. The diameter of the hole 36 in each of the legs 18 and 23 may exceed the diameter of the bolt 34 if desired to permit vertical movement 10 of the rail 17 as the load shifts from tie to tie when a train passes thereover. Also, the vertical grip of the arms 33 on the base 16 of the rail 17 is only that which will normally retain the base 16 seated on the anchor plates 12 and 13 so that longitudinal travel of the base 16 is permitted under those arms 33.

A safety feature is embodied in respect to the clamps 28 and 29 in case the nut 39 loosens or the bolt 34 may break. For this purpose, each 20 of the clamps is provided, Fig. 4, with a post 40 of any desired cross section, herein shown as substantially rectangular. The post 40 is located to extend horizontally from the inner face of the leg 30 to be removed somewhat from the axis of the hole 35, and the length of the post 40 is sufficient to permit it to extend through both legs 18 and 23 when the clamps are installed and to permit adjustment of the clamps in respect to the legs 30 toward and away from those legs. 25 The legs 18 and 23 are provided with a pair of holes 41 and 42 therethrough so as to receive the posts 40 of the respective brackets 28 and 29 therethrough. The outer ends of the posts 40 carry some detachable securing means, herein 30 shown as cotter pins 43 which may be easily removed to permit removal of the clamps when desired. In any event, the cotter pins 43 will be of sufficient diameter to prevent withdrawal of the posts 40 under normal operations for at 35 least a short time, or at least until such time as the track inspector may detect the condition wherein the bolt 34 is not properly functioning. As indicated in the drawing, by locating the post 40 off to one side of the central vertical plane through each clamp 28 and 29, and by providing the correspondingly spaced apart holes 41 and 42 in the legs of the anchor plates, the clamps 28 and 29 do not have to be made in right and left hand construction.

The clamps 28 and 29 may, of course, be varied in respect to their exact conformation, particularly where the clamps are to be secured on curves and the like or at switches where the rail 17 is preferably braced against tendency to upset. In this regard, the clamp 29, for example, may have an upper end 44 extending from the arm 33 to extend along the web of the rail to brace it, whereby no additional brace members are required.

While I have herein shown and described my invention in the one particular form, it is obvious that structural changes may be employed, such as in the shapes of the legs under the anchor plates, the use of one anchor plate fixed to one leg and extending over another leg, for example, as indicated in Figs. 8 and 9 of the drawing wherein the one anchor plate 50 is an integral part of the leg 18 to extend over the leg 23, the use of two bolts to secure the clamps in position in place of the one shown, the engagement of the safety posts carried by the clamps, and other mechanical features, all without departing from the spirit of the invention, and I therefore 65 do not desire to be limited to that precise form

beyond the limitations as may be imposed by the following claims.

I claim:

1. In a rail cross tie and fastening means, a channel tie with legs upwardly directed; an anchor plate of a length sufficient to rest upon and across the upper ends of said tie legs; a pair of legs disposed under said plate to have lower foot ends bear on the tie web interconnecting said tie legs, and transmit a load from the plate to the web thereby; each of said plate legs having a pin projecting therefrom from one vertical edge portion, said plate legs being placed one against the other to have the pin of one projecting oppositely from the pin of the other; said tie legs being provided with predetermined located holes to receive and hold said pins to fix said legs in position longitudinally of the tie; a pair of clamps, each having an upper rail base engaging arm extending along and above outer edge portions of said plate and a lower foot portion to extend below said plate; bolt means for interengaging said clamp foot portions through said plate legs; and means variably spacing said clamp foot portions from either outer face of said plate legs, whereby a rail engaged between said clamp arms may be variably positioned on said plate for desired track gauge.

2. In a rail cross tie and fastening means, a channel tie with legs upwardly directed; an anchor plate of a length sufficient to rest upon and across the upper ends of said tie legs; a pair of legs disposed under said plate to have lower foot ends bear on the tie web interconnecting said tie legs, and transmit a load from the plate to the web thereby; each of said plate legs having a pin projecting therefrom from one vertical edge portion, said plate legs being placed one against the other to have the pin of one projecting oppositely from the pin of the other; said tie legs being provided with predetermined located holes to receive and hold said pins to fix said legs in position longitudinally of the tie; a pair of clamps, each having an upper rail base engaging arm extending along and above outer edge portions of said plate and a lower foot portion to extend below said plate; bolt means for interengaging said clamp foot portions through said plate legs; and means variably spacing said clamp foot portions from either outer face of said plate legs, whereby a rail engaged between said clamp arms may be variably positioned on said plate for desired track gauge; said plate being fixed to at least one of said legs.

3. In a rail cross tie and fastening means, a channel tie with legs upwardly directed; an anchor plate of a length sufficient to rest upon and across the upper ends of said tie legs; a pair of legs disposed under said plate to have lower foot ends bear on the tie web interconnecting said tie legs, and transmit a load from the plate to the web thereby; each of said plate legs having a pin projecting therefrom from one vertical edge portion, said plate legs being placed one against the other to have the pin of one projecting oppositely from the pin of the other; said tie legs being provided with predetermined located holes to receive and hold said pins to fix said legs in position longitudinally of the tie; a pair of clamps, each having an upper rail base engaging arm extending along and above outer edge portions of said plate and a lower foot portion to extend below said plate; bolt means for interengaging said clamp foot portions through said plate legs; and means variably spacing said clamp foot portions from either outer face of said plate legs, whereby a rail engaged between said clamp arms may be variably positioned on said plate for desired track gauge.

either outer face of said plate legs, whereby a rail engaged between said clamp arms may be variably positioned on said plate for desired track gauge; said anchor plate being in two sections,

5 one section secured to one of said plate legs, and the other section secured to the other of said legs, the two sections abutting along a line substantially within the central vertical plane of the rail.

10 4. A rail tie and fastening means comprising a metal tie channel iron in shape to be used legs turned upwardly to have the web form a road bed bearing surface; said tie legs each being provided with a hole to determine approximately the track gauge; a pair of substantially identical L shaped members, each having an upper plate to rest on and extend across the upper ends of said tie legs, and a downturned integral leg sufficiently long and shaped to enter between said tie legs to bear at least on the central portion of said tie web, and to abut by portions at least of the vertical edge portions the opposing faces of said tie legs; a pin projecting from a vertical edge portion of each of said members at a position below the tops of said tie legs, whereby upon placing two of said members to form said pair, back to back with their legs between said tie legs, a pin will extend from said pair in opposite directions, and enter the respective said holes; clamp member for each side of said pair of said L shaped members formed to have a rail clamp arm extend above and overhang the said plates; and a bolt extending through said clamp members and said member legs for drawing the clamps one toward the other with said member legs intervening.

30 5. A rail tie and fastening means comprising a metal tie channel iron in shape to be used legs turned upwardly to have the web form a road bed bearing surface; said tie legs each being provided with a hole to determine approximately the track gauge; a pair of substantially identical L shaped members; each having an upper plate to rest on and extend across the upper ends of said tie legs, and a downturned integral leg sufficiently long and shaped to enter between said tie legs to bear at least on the central portion of said tie web, and to abut by portions at least of the vertical edge portions the opposing faces of said tie legs; a pin projecting from a vertical edge portion of each of said members at a position below the tops of said tie legs, whereby, upon placing two of said members to form said pair, back to back with their legs between said tie legs, a pin will extend from said pair in opposite directions,

40 55 and enter the respective said holes; a clamp member for each side of said pair of said L shaped members formed to have a rail clamp arm extend above and overhang the said plates; and a bolt extending through said clamp members and said member legs for drawing the clamps one toward the other with said member legs intervening; each of said L shaped member legs having a pair of holes therethrough equally spaced from the center line of said bolt; a safety member fixed off center to each of said clamp members to pass respectively through said member holes; and means engaging said safety members to restrain withdrawal from the holes.

60 6. In a rail cross tie and fastening means, a channel tie with legs upwardly directed; an anchor plate of a length sufficient to rest upon and across the upper ends of said tie legs; a pair of legs disposed under said plate to have lower foot ends bear on the tie web interconnecting said tie legs, and transmit a load from the plate to the

web thereby; each of said plate legs having a pin projecting therefrom from one vertical edge portion, said plate legs being placed one against the other to have the pin of one projecting oppositely from the pin of the other; said tie legs being provided with predetermined located holes to receive and hold said pins to fix said legs in position longitudinally of the tie; a pair of clamps, each having an upper rail base engaging arm extending along and above outer edge portions of said plate and a lower foot portion to extend below said plate; bolt means for interengaging said clamp foot portions through said plate legs; and means variably spacing said clamp foot portions from either outer face of said plate legs, whereby a rail engaged between said clamp arms may be variably positioned on said plate for desired track gauge; and safety means independent of said bolt means securing said clamps to said plate legs.

7. In a rail cross tie and fastening means, a channel tie with legs upwardly directed; an anchor plate of a length sufficient to rest upon and across the upper ends of said tie legs; a pair of legs disposed under said plate to have lower foot ends bear on the tie web interconnecting said tie legs, and transmit a load from the plate to the web thereby; each of said plate legs having a pin projecting therefrom from one vertical edge portion, said plate legs being placed one against the other to have the pin of one projecting oppositely from the pin of the other; said tie legs being provided with predetermined located holes to receive and hold said pins to fix said legs in position longitudinally of the tie; a pair of clamps, each having an upper rail base engaging arm extending along and above outer edge portions of said plate and a lower foot portion to extend below said plate; bolt means for interengaging said clamp foot portions through said plate legs; and means variably spacing said clamp foot portions from either outer face of said plate legs, whereby a rail engaged between said clamp arms may be variably positioned on said plate for desired track gauge; and safety means independent of said bolt means securing said clamps to said plate legs; said safety means consisting of a post on each clamp extending through said plate legs, and an engagement on the extended end thereof.

8. In a rail cross tie and fastening means, a channel tie with legs upwardly directed; an anchor plate of a length sufficient to rest upon and across the upper ends of said tie legs; a pair of legs disposed under said plate to have lower foot ends bear on the tie web interconnecting said tie legs, and transmit a load from the plate to the web thereby; each of said plate legs having a pin projecting therefrom from one vertical edge portion, said plate legs being placed one against the other to have the pin of one project-

ing oppositely from the pin of the other; said tie legs being provided with predetermined located holes to receive and hold said pins to fix said legs in position longitudinally of the tie; a pair of clamps, each having an upper rail base engaging arm extending along and above outer edge portions of said plate and a lower foot portion to extend below said plate; bolt means for interengaging said clamp foot portions through said plate legs; and means variably spacing said clamp foot portions from either outer face of said plate legs, whereby a rail engaged between said clamp arms may be variably positioned on said plate for desired track gauge; and safety means independent of said bolt means securing said clamps to said plate legs; each of said plate legs having a pair of holes therethrough equally spaced from the center of said bolt means; and said safety means comprising a post on each clamp spaced to enter and extend through the respective plate leg holes, and means on the extended clamp post ends restricting withdrawal from the plate legs.

9. In a rail cross tie and fastening means, a channel tie with legs upwardly directed; an anchor plate of a length sufficient to rest upon and across the upper ends of said tie legs; a pair of legs disposed under said plate to have lower foot ends bear on the tie web interconnecting said tie legs, and transmit a load from the plate to the web thereby; each of said plate legs having a pin projecting therefrom from one vertical edge portion, said plate legs being placed one against the other to have the pin of one projecting oppositely from the pin of the other; said tie legs being provided with predetermined located holes to receive and hold said pins to fix said legs in position longitudinally of the tie; a pair of clamps, each having an upper rail base engaging arm extending along and above outer edge portions of said plate, and a lower foot portion to extend below said plate; bolt means for interengaging said clamp foot portions through said plate legs; and means variably spacing said clamp foot portions from either outer face of said plate legs, whereby a rail engaged between said clamp arms may be variably positioned on said plate for desired track gauge; said spacing means consisting of washers carried by said bolt means between said anchor plate legs and said clamp foot portions.
